DESIGN FOR A LAMP

Abraham Hassen and Maley Meyers, Chicago, Ill.

Application November 8, 1937, Serial No. 72,672

Term of patent 3½ years

To all whom it may concern:

Be it known that Abraham Hassen and Maley Meyers, both citizens of the United States, residing in Chicago, Illinois, have invented a new, original, and ornamental Design for a Lamp, of which the following is a specification, reference being had to the accompanying drawing, forming part thereof.

We claim:

The ornamental design for a lamp, as shown.

ABRAHAM HASSEN.
MALEY MEYERS.
